UNITED STATES PATENT OFFICE.

EDGAR F. FRUEHBECK, OF MARFA, TEXAS.

ENGINE-STARTER.

1,099,123.

Specification of Letters Patent.

Patented June 2, 1914.

Application filed August 14, 1913. Serial No. 734,677.

To all whom it may concern:

Be it known that I, EDGAR F. FRUEHBECK, a citizen of the United States, residing at Marfa, in county of Presidio and State of Texas, have invented certain new and useful Improvements in Engine-Starters, of which the following is a specification.

This invention relates to new and useful improvements in engine starters, and has more particular relation to starters for internal combustion engines.

The object of the invention is to provide a device of the character described which is operated by compressed air and which may be brought into operative connection with the fly wheel of the engine to be started, whereby said fly wheel is rotated.

Another object of the invention resides in the provision of a mechanism which in turn is operated by the fly wheel of the engine, while said engine is in motion, and which is provided to maintain a sufficient degree of compression in the storage tank.

A further feature of the invention resides in the provision of a mechanism which will automatically connect the compressing mechanism with the fly wheel of the engine when the compression in the storage tank is lowered to a predetermined point.

With the above and other objects in view, the invention has particular relation to certain novel features of construction, operation and arrangement of parts, an example of which is given in this specification and illustrated in the accompanying drawing, wherein the figure shows a side elevation of the device, partially in section.

Referring particularly to the drawing, the numeral 1 indicates a supply pipe which leads from a suitable compression reservoir, or chamber, of the usual and well known construction, and which it has not been thought necessary to illustrate in the drawing.

The numeral 2 designates a turbine wheel which is rigidly mounted on the shaft 3 and is inclosed by the casing 4.

Suitable reducing gears 5 and 6 are provided, the former of which is rigidly mounted upon the shaft 3 and the latter of which is rigidly mounted upon the drive shaft 7, said gears intermeshing and being inclosed by the casing 8 which is cast integral with the casing 4. Said casings are provided with suitable bearings for the shafts 3 and 7, as shown. The shaft 7 is provided

with a loosely mounted drive wheel 9 which is in rolling contact with the fly wheel of the engine, indicated in dotted lines. The shaft 7 extends back a considerable distance and rotates in the alined bearings 10 and 11, formed in the supporting frame work of the device, and slidably mounted thereon, but keyed thereto so as to rotate therewith is the clutch member 12, forming with the drive wheel 9 the ordinary cone friction clutch and by means of which the drive shaft 7 may be clutched with or de-clutched from said drive wheel 9.

Two compression cylinders 13 and 14 are provided, which may be cast integral, if it is so desired, and each of which are provided with air inlets, numbered, respectively, 15 and 16. These cylinders are provided with pistons 17 and 18 which are driven through the respective piston rods 19 and 20, pivoted at one end to their respective pistons and at their other ends to the respective wrists 21 and 22, of the shaft 7. From the respective cylinders 13 and 14 lead the pipes 23 and 24 equipped, respectively, with check valves 25 and 26, of the ordinary construction, and said pipes communicate with the supply pipe 1. The cylinders 13 and 14 are also provided, respectively, with relief pipes 27 and 28 controlled by the ordinary valves 29 and 30, for a purpose to be hereinafter set forth.

Cast integral with and extending laterally from the cylinder 13 is the cylinder 31 having the plunger 32 reciprocating therein and which is fixed to the inner end of the plunger rod 33 which operates through the stuffing box 34 carried by the cylinder head 35. Interposed between the plunger 32 and the cylinder head 35 and surrounding the plunger rod 33 is a strong coil spring 36. A lever 37 is provided which is pivoted to the fulcrum 38. One end of this lever is pivoted to the outer end of the plunger rod 33 and the other end has a pivotal connection with the clutch member 12.

The supply pipe 1 is connected with the cylinder 31 through the pipe 39 and the pipe 39 has a relief outlet 40 controlled by the ordinary three-way valve 41 so that the cylinder 31 may be connected directly with the supply pipe 1 or may be relieved of its compression through the relief outlet 40.

Leading from the supply pipe 1 is the pipe 42 having a discharge nozzle 43 which discharges against the turbine 2 and a three-

way valve 44 is provided which controls the said pipe 42. The stem of the valve 29 has two arms 44' and 45 extending upwardly therefrom and the stem of the valve 30 has the arm 46 projecting upwardly therefrom, the free ends of the arms 45 and 46 being connected by a link 47 whose ends are pivoted to the free ends of the respective arms 45 and 46. The stem of the valve 41 has an upwardly extending arm 48 and the free ends of the arms 44' and 48 are connected by the link 49 whose ends are pivoted to the free ends of said respective arms. The stem of the valve 44 has an upwardly extending arm 50 and the free ends of the arms 44 and 50 are connected by the link 51 whose ends are pivoted to the free ends of said respective arms. A push rod 52 is provided whose lower end is pivoted to the upper end 20 of the arm 50 and which extends up through the foot board 53 of the vehicle and has a sliding bearing therein. This push rod extends through a cage 54 within which, and surrounding said rod is a strong coil spring 25 55 which rests against the end of said cage and the collar 56 carried by the rod 52.

The operation of the device is as follows:—When it is desired to start the engine, the push rod 52 is forced downwardly 30 by the foot of the operator, overcoming the resistance of the spring 55 which operates through the arm 50 to open the pipe 42 and permit the compressed air to pass therethrough and to start the turbine 2. At the 35 same time the valves 29, 30 and 41 are opened so as to relieve the pressure from the cylinders 18, 14 and 31. When the pressure is relieved from the cylinder 31, the plunger 32 is driven back by the spring 36 with 40 the result that the clutch member 12 is driven forward through the operation of the lever 37 and clutched with the drive wheel 9. Rotation is imparted from the turbine 2 to the shaft 7 and to the clutch member 12, carried thereby, through the gears 5 and 6. Rotation is imparted to the fly wheel of the engine from the drive wheel 9 which is in rolling contact therewith. After the 45 engine has started, the push rod 52 is released and assumes its original position through the resistance of the coil spring 55. When the push rod 52 assumes its original position, it operates through the mechanism connected therewith, as hereinbefore described, to close the pipe 42 and the relief pipes 27 and 28 and also to close the relief outlet 40 and to communicate the cylinder 31 with the supply pipe 1, through the pipe 39. The air pressure driven through the 50 pipe 39 will operate to force the plunger forward which will operate through the lever 37 to withdraw the clutch member 12 from engagement with the drive wheel 9 and the rotation of the shaft 7 will be 55 stopped. During the operation just de-

scribed, the pistons 17 and 18 will reciprocate back and forth in their cylinders, but inasmuch as relief pipes 27 and 28 are open, the reciprocation of said pistons will be free.

In case the pressure in the storage reservoir should become too low, the device is arranged to automatically restore said pressure to the desired point. If, while the engine is in operation, the pressure should become low, it is apparent that the spring 36 70 would operate to drive the plunger 32 backward in its cylinder, with the result that the clutch member 12 would be clutched with the drive wheel 9 through the operation of the lever 37. The drive wheel 9 is constantly rotating while the engine is in operation and rotation would be immediately imparted to the shaft 7 which would operate the air compressors, as hereinbefore described, and restore the desired compression 75 to the compression reservoir. 80

What I claim is:—

1. A device of the character described including a fluid pressure turbine and means for applying fluid under compression thereto, whereby said turbine is rotated, a shaft, means operatively connecting said turbine with said shaft, an engine fly wheel, a rotatable member in operative connection with said fly wheel and loosely mounted on said shaft, a clutch member slidably mounted upon the shaft, but fixed against relative rotation thereon, a mechanism operatively connected with the clutch member and normally holding said member in engagement with the rotatable member carried by said shaft and means for applying fluid pressure to said mechanism whereby said clutch member is disengaged from said rotatable member. 90

2. A device of the character described, including a fluid pressure turbine, a supply pipe for conducting fluid under compression, means for conducting the fluid from said supply pipe and discharging the same against said turbine, whereby the turbine is rotated, a shaft, means operatively connecting the turbine with the shaft, an engine and a fly wheel carried thereby, a friction drive wheel loosely mounted on the 100 shaft and in rolling contact with said fly wheel of said engine, a clutch member slidably mounted upon said shaft, but fixed against relative rotation thereon, a mechanism operatively connected with the clutch member and normally holding said member in engagement with said drive wheel, whereby said wheel is driven by said shaft and means for applying fluid pressure from said supply pipe to said mechanism, whereby said clutch member is disengaged from said drive wheel. 110

3. A device of the character described, including a fluid pressure turbine, a supply pipe for conducting fluid under compression 120

sion, means for conducting the fluid from said supply pipe and discharging the same against said turbine, whereby the turbine is rotated, means for controlling the passage 5 of the fluid through said supply pipe, a shaft, means operatively connecting the turbine with the shaft, an engine, a fly wheel driven by said engine, a friction drive wheel loosely mounted on the shaft and in operative 10 contact with said fly wheel, a clutch member slidably mounted upon said shaft, but fixed thereon against relative rotation, a mechanism operatively connected with the clutch member and normally holding 15 said member in engagement with said drive wheel whereby said wheel is driven by said shaft and means for applying fluid pressure from said supply pipe to said mechanism, whereby said clutch member is disengaged from said drive wheel.

4. A device of the character described including a fluid pressure turbine and means for applying fluid under compression thereto, whereby said turbine is rotated, a shaft, means operatively connecting said turbine 20 with said shaft, an engine, a fly wheel driven

by said engine, a friction drive wheel loosely mounted on said shaft and in peripheral contact with said fly wheel of said engine to be started, a clutch member slidably mounted 30 upon the shaft but fixed against relative rotation thereto, a pivotally mounted lever, one end of which has connection with said clutch member, a fluid compression cylinder, a plunger therein, a plunger rod fixed 35 at one end to said plunger and whose other end is pivoted to said lever, a resilient member operating against said plunger rod and normally holding said clutch member in engagement with said drive wheel, and means 40 for introducing fluid pressure in said cylinder behind said plunger, whereby the pressure of said resilient member is overcome and the clutch member disengaged from 45 said drive wheel.

In testimony whereof I have signed my name to this specification in the presence of two subscribing witnesses.
